Attorney

UNITED STATES PATENT OFFICE

CHARLES H. MEAD, OF BECKLEY, WEST VIRGINIA

TRACK SANDING PIPE

Application filed May 20, 1931. Serial No. 538,860.

The present invention relates to new and useful improvements in track sanding pipes for use particularly on rail vehicles, such as mine cars, locomotives, street cars and rail-
 5 road cars and has for its primary object to provide a device of this character embodying novel means for maintaining the discharge end of the pipe at all times above the rail in a manner to assure the discharge thereonto
 10 of practically all of the sand.

In the accompanying drawings which form part of this application the embodiments illustrated, while preferred, are simply by way of exemplification.

15 In the drawings:—

Figure 1 is a view in side elevation showing a track sanding pipe in accordance with this invention mounted in position on a locomotive.

20 Figure 2 is a view in vertical section through the sanding pipe.

Figure 3 is a view in side elevation showing a slightly modified form of the sanding pipe.

25 In the drawings, the reference numeral 1 designates one of the drive wheels of a steam locomotive traveling on the rail 2. The device constituting the present invention is designated generally by the reference number 30 and comprises a stationary section or pipe 4 which, if desired or necessary, is mounted on a base 5 of electricity insulating material which, in turn, is secured in any suitable manner on the locomotive or other rail vehicle. The base 5 is provided with an opening 6 for the reception of the delivery pipe 7 from the sand box or other source of supply (not shown).

An angular nozzle 8 is secured to the lower 40 end portion of the stationary pipe 4 for swinging movement in a horizontal plane by a swivel connection or joint 9 which may be of any suitable type or construction. The nozzle 8 has its lower or discharge end disposed just above the rail 2 forwardly of the wheel 1.

The nozzle 8 and also, if desired, the pipe 4 are magnetized and for this reason are formed from a suitable metal. When in use, the nozzle 8 being magnetized, will be attracted to the rail 2 and thereby maintained

in position thereover at all times, as when the rounding curves or when the rail vehicle may swing or sway. The use of magnetism for maintaining the nozzle in proper position relative to the rail at all times is the gist of 55 the present invention.

In the slightly modified form of the invention illustrated in Figure 3 of the drawings, the swinging nozzle 8 has mounted thereon adjacent its lower or free end, and 60 in a manner to be disposed adjacent the top of the rail 2 a magnet 10. In this form of the invention any suitable type of magnet may be mounted on the nozzle. The magnet 10 is, of course, attracted to the rail, thereby 65 maintaining the nozzle in proper position relative thereto at all times.

Having thus described my invention what I claim as new is:—

1. A magnetized track sanding pipe. 70
2. A track sanding pipe constructed of magnetized metal.
3. A track sanding pipe comprising a rotatably mounted magnetized discharge nozzle. 75
4. A track sanding pipe comprising a discharge nozzle constructed of magnetized metal.
5. A track sanding pipe comprising a fixed section and an angular discharge nozzle 80 mounted for swinging movement in a horizontal plane on said fixed section, said nozzle being constructed of magnetized metal.
6. A track sanding pipe comprising, in combination, a discharge nozzle and a magnet 85 mounted thereon.

In testimony whereof I affix my signature.

CHARLES H. MEAD.
